CLAIM

The ornamental design for an augmented reality headset as shown and described.

DESCRIPTION

FIG. 1 is a front view of an augmented reality headset according to our design;

FIG. 2 is a back view of the augmented reality headset;

FIG. 3 is a left side view of the augmented reality headset;

FIG. 4 is a right side view of the augmented reality headset;

FIG. 5 is a top view of the augmented reality headset;

FIG. 6 is a bottom view of the augmented reality headset;

FIG. 7 is a front perspective view of the augmented reality headset; and,

FIG. 8 is a back perspective view of the augmented reality headset.

The parts shown by broken lines in the figures are for the purpose of illustrating environment only and are not part of the claimed designs; the thin lines and hatchings in the figures represent contours only and do not illustrate an ornamentation or decoration on the surface of the product.

1 Claim, 8 Drawing Sheets
